UNITED STATES PATENT OFFICE.

JOSEPH S. FIALA, OF CHICAGO, ILLINOIS.

LAUNDRY STAND.

Application filed January 18, 1922. Serial No. 530,098.

To all whom it may concern:

Be it known that I, JOSEPH S. FIALA, a citizen of the United States, and a resident of the city of Chicago, county of Cook, and 5 State of Illinois, have invented certain new and useful Improvements in Laundry Stands, of which the following is a specification.

My invention relates to improvements in 10 laundry stands and has for its principal object the provision of an improved construction of this character which will be highly efficient in use.

A further object of the invention is the 15 provision of an all metal stand which will be light in structure and durable in use, one consisting of extensible supporting elements.

Other objects will appear hereinafter.

The invention consists in the combinations and arrangements of parts hereinafter described and claimed.

The invention will be best understood by reference to the accompanying drawings forming a part of this specification, and in 25 which,

Fig. 1 is a top plan view of a laundry stand embodying the invention showing the supporting elements in their extended position;

30 Fig. 2 is a sectional detail view of the same, taken substantially on line 2—2 of Fig. 1;

Fig. 3 is a side elevational view, of the same, showing the supporting elements in 35 their retracted position;

Fig. 4 is a perspective view of a wringer support embodied in the invention;

Fig. 5 is a fragmentary perspective view 40 of one of the corners of the stand to more fully illustrate the extensible parts embodied in the invention;

Fig. 6 is an enlarged sectional detail view taken substantially on line 6—6 of Fig. 3;

Fig. 7 is a sectional detail view taken substantially on line 7—7 of Fig. 5; and

Fig. 8 is a fragmentary sectional detail view taken substantially on line 8—8 of Fig. 2.

The preferred form of construction, as 50 illustrated in the drawings, comprises extensible supporting elements A and B arranged to receive a wash tub 10 and a wash basket 11, when in use. The supporting element A comprises a frame 12 formed from 55 a continuous angular member bent in the shape of a rectangle, as shown, the opposite

ends of said member being spot-welded or fixedly secured together by any suitable securing means. The frame 12 is reenforced by angular reenforcing members 13, extending parallel with the sides of the frame and fixedly secured to the ends thereof by spot-welding or the like. The reenforcing members 13 are reenforced by U-shaped braces 14 which are fixedly secured to the sides 60 of the frame 12 and the reenforcing members 13. The frame supporting legs 15 are each formed from a single piece of wire, bent centrally upon itself and twisted as illustrated in the drawings. The upper opposite end portions 16 of the wires are bent so as to diverge from each other, and the outer ends of said portions are bent to form a loop 17 through which a nut receiving bolt 18 passes for fixedly securing the legs to the 65 sides and ends of the frame 12, as shown. The legs 15 are reenforced by wire members 19, the ends of which are threaded to receive nuts 20 and bent substantially at right angles passing through openings formed in 70 bracket members 21 carried by each of the legs. The wire members 19 are reenforced by transversely extending metal strips 22 which are secured thereto by bending the opposite ends back upon the strips so as to 75 embrace the wire members 19, the bent ends being fixedly secured to the said strips by spot-welding or suitable rivets. The frame 80 12 carried oppositely disposed channel shaped guide members 23 which extend parallel with respect to the sides of the frame and are supported in position by hangers 24.

Associated with the supporting element A and mounted on one end thereof is a rectangular support C, said support comprising 95 vertically extending socket members 25 provided with lateral ears 26 to facilitate securing the socket members to the frame 12 in spaced relation with respect to each other. The socket members 25 are braced 100 by wire members 26' which are secured to lateral ears 26, formed on the socket members 25, and to the opposite sides of the frame 12 by suitable nut receiving bolts 27. A drain guide 28, having opposite downwardly inclined drain portions 29 is carried 105 by leg portions 30 which are secured to the drain guide 28 by any suitable means, said drain guide being formed of sheet metal and provided with upwardly turned sides 31 as 110 best shown in Fig. 4. A wringer receiving bar 32 is mounted to centrally transverse

the drain guide 28 and is secured to upwardly extending portions 33 formed integral with the upwardly turned ends 31, said portions 33 being provided with lateral flanges 34 which are bent to embrace the sides of the wringer bar 32. At the point where the wringer clamps 35 engage the bar 32, I provide metal reenforcing plates 36 to prevent the clamps from cutting into the bar 32, which in this instance is formed of wood. If desired the bar 32 may be formed of sheet metal or be cast. When such is the case the plates 36 are not needed. The leg portions 30 are adapted to pass into the socket members 25 and may be adjusted in any desired position, said legs being held in their adjusted position by hand bolts 37 which are carried by the socket members 25 as shown. To support the socket members more rigidly, I provide a wire member 38 which is arranged between the socket members and secured to lateral ears 39 formed thereon.

The extensible supporting element B comprises an angular frame 40 formed from a single piece of material bent in substantially the same manner as the angular frame member 12 of the supporting element A. The opposite sides of the frame 40 are mounted to slidably engage the channel shaped guide members 23. The frame 40 is also reenforced by angular reenforcing members 41 which are secured thereto by spot-welding or the like. The outer end of the said frame 40 carries supporting legs 42 which are formed and connected to the said frame substantially in the same manner as the supporting legs 15. The supporting legs 42 are braced by wire members 43 and 44, the wire members 43 being secured to bracket members 45 carried by each of the legs 42. The other wire members 44 are secured to the bracket members 45 and the end 45' of the frame 40. The outward movement of the supporting element B is governed by stop plates 46 carried on the end 45' of the frame 40 opposite the corners thereon, said stops being adapted to engage depending U-shaped stop members 47 which are carried by the frame 12, as best shown in Fig. 5.

From the construction as herein set forth, I provide extensible supporting elements, the operation of which is obvious from the description herein stated. When the supporting elements are in their extended position they are adapted to support a wash tub on one side of the wringers support C and a wash basket on the opposite side, or support a wash tub on both sides of the said wringer support, as will best meet the requirements of the user.

To facilitate the extension of the supporting elements A and B, I provide a handle 48 arranged between the reenforcing members 13, and a handle 49 fixedly secured to

the end of the frame 40 between the members 41, as shown. By grasping the handles 48 and 49 the supporting elements can be easily extended and retracted. As stated herein the wire members 26' serve to brace the socket members 25, however, they also serve another purpose. As best shown in Fig. 2, the sides of the tub 10 engage the wire members 26', which prevents the tub 10 from being pushed off the extensible supporting element A, especially when pressure is applied to the tub when the user of the laundry stand is in the act of rubbing the clothes on a wash board.

When the extensible parts are in their retracted position the same are locked in said position by means of a hook 50 which is swingingly carried by one of the wire members 19, said hook being adapted to engage the wire member 43 when in locking position.

The laundry stand herein set forth being formed of a light metal enables the user to conveniently move the stand from one place to another. The cost of manufacturing my improved stand is small and the stand will be serviceable to the house-wife.

While I have illustrated and described the preferred form of construction for carrying my invention into effect, this is capable of variation and modification without departing from the spirit of the invention. I, therefore, do not wish to be limited to the precise details of the construction set forth, but desire to avail myself of such variations and modifications as come within the scope of the appended claims.

Having described my invention, what I claim as new and desire to secure by Letters Patents is:

A laundry stand including supporting elements slidably connected together and comprising tops having rim portions angularly-shaped in cross section, oppositely disposed channel members arranged in parallel relation beneath the top of one of said supporting elements and adapted to slidably receive the top of the other supporting element, means carrying said channel members in position beneath the top of the adjacent supporting element, and substantially U-shaped members carried at one end of one of said supporting elements adapted for engagement with the rim of the other of said supporting element for limiting movement of said supporting element in one direction.

In testimony whereof I have signed my name to this specification in the presence of two subscribing witnesses.

JOSEPH S. FIALA.
